Primary Examiner — Catheri Oliver-Garcia*Assistant Examiner* — Rebekah Caruso(57) **CLAIM**

The ornamental design for a fascial tool, as shown and described.

DESCRIPTION

FIG. 1 is a perspective view of a fascial tool;

FIG. 2 is a front elevation view thereof, the rear elevation view being a mirror image thereof;

FIG. 3 is a left elevation view thereof, the right elevation view being a mirror image thereof;

FIG. 4 is a top plan view thereof;

FIG. 5 is a bottom plan view thereof; and,

FIG. 6 is a cross section view shown along line 6-6 of FIG. 2. The cutaway symbols illustrated in break lines in the drawings indicate a symbolic break in the length of the design for the fascial tool indicating no particular length. The appearance of any portion of the article between the break lines forms no part of the claimed design.
